UNITED STATES PATENT OFFICE.

WILLIAM W. DEAN, DECEASED, LATE OF LOWELL, MASSACHUSETTS; BY MARY E. DEAN, EXECUTRIX, OF BIRMINGHAM, MICHIGAN, ASSIGNOR TO THE GENERAL PHONOGRAPH MANUFACTURING COMPANY, OF ELYRIA, OHIO, A CORPORATION OF OHIO.

PUSH-BUTTON SWITCH.

Application filed December 8, 1923. Serial No. 679,301.

To all whom it may concern:

Be it known that WILLIAM W. DEAN, a citizen of the United States, now deceased, and who resided at Lowell, Massachusetts, did prior to his death invent certain new and useful Improvements in Push-Button Switches, of which the following is a full, clear, and exact disclosure of one form.

This invention relates to push button switches for controlling electric circuits, and especially for devices of this kind which are employed for operating the warning signal apparatus for automobiles, motor cycles, and other similar vehicles.

15 An object of my invention is to provide a push button switch having an axially movable contact member which is readily operated by pressure against a button which presents a large operating area and which 20 will be operated, without distracting the attention of an operator, when slight pressure is applied thereto at any point within the circumference of the outer surface thereof.

Another object of my invention is to provide 25 a switch of the character described in which a contact member can be easily moved in a single axial direction to form a circuit when pressure is applied against a push button.

30 Another object of my invention is to provide a switch with a bearing which permits a contact member to be easily moved in a single axial direction to form an electric circuit, when pressure is applied against any 35 point on the surface of a push button attached to the contact member.

Other objects and the invention itself will 40 be better understood from the accompanying description of an embodiment of the invention.

In the drawings illustrating my invention—

Fig. 1 is a cross section of an embodiment 45 of my invention taken on the line 1—1 of Fig. 2;

Fig. 2 is an end elevation of the embodiment 50 of my invention illustrated in Fig. 1;

Fig. 3 is a side elevation of the embodiment 55 of my invention illustrated in Fig. 1; and

Fig. 4 is a sectional view of the embodiment 60 of my invention illustrated in Fig. 1 taken on line 4—4 of Fig. 2.

Referring to the embodiment of my invention illustrated in the drawing by characters of reference, 10 illustrates a cylindrical frame or base member, formed of insulating material, having an end wall 11 and an open end 12. A hollow elongated annular bearing housing 13 is formed integrally with the frame member, projecting centrally from the end wall 11 toward the open end 12, of the base member.

A hollow cylindrical bushing or bearing 14 is carried within, and is of substantially the same length as the housing 13. A cylindrical stem 15 extends through and is mounted within the bearing 13, being free therein to rotate, and to reciprocate in a single axial direction. The end of the stem is provided with an opening which is threaded and receives the threaded shank of a contact stud 16, the head of the stud being large enough to prevent the stem from being removed through the end wall of the frame. The stem and the stud are referred to as a contact member.

A mushroom shaped push button, formed of conventional insulating material, is preferably molded upon the projecting end of the stem. The push button is of a mushroom shape, of such diameter that it will telescope over the adjacent end of the frame. The button includes a central portion and an outer skirt portion 20, the outer surfaces of which merge into a continuous convex curve, the surface of the skirt portion extending in a convex curve outwardly from the central portion. Such an exterior button surface provides a maximum area against which an operator can press to successfully and easily move the stem axially in its bearing as sufficient purchase can be obtained against the outer button surface at any point with an area bounded by the extreme outer circumference of the skirt.

When the contact member is in maximum extended position, the head of the stud 16 engages the end of the bearing 13 and the push button is spaced from the end wall 11 of the frame member, being normally maintained in such relations by a coil spring 21 extending around the portion of the stem which projects from the end wall of the frame member, through the bearing housing 13 and the bearing 14. The opposite

ends of the spring bear against the inner surface of the central portion of the push button and the outer surface of the end wall of the frame member. The annular flange 20 of the push button is of sufficient size to enclose the adjacent end of the frame member, remaining in such relation at all times when assembled.

Oppositely disposed hollow terminal posts 22 are molded within the wall of the base member and extend longitudinally therein, the ends of such posts being provided with contact wings 23 which extend arcuately within the end wall of the base member. Recesses 24 are formed in the end of the wall of the base member to permit wires 35 to extend into the hollow terminals where they are clamped by screws 25, which project transversely through the wall of the frame member and enter the hollow terminals. Oppositely disposed recesses 26 are provided intermediate the terminal posts 23, and one end of a spring contact finger 27 is secured against one of the arcuate wings of the terminal posts, at the base of each recess, by threaded studs 28 which are screwed through the end wall of the frame member. The contact fingers 27 extend longitudinally beside the bearing housing 13 and project beyond the end thereof, having bent ends 29 extending toward each other.

The terminals are connected by wires 35 to a source of electric supply, and are in circuit with an automobile horn, or the like, 35 and the arcuate wings or arms 23 are connected to the contact fingers 27. When the push button is pressed against by an operator, the stem 15 will be moved in a single axial direction through the bearing housing and bearing, until the stud 16 engages the bent ends 29 of the fingers 27, completing the circuit. When the pressure against the button is released the spring 21 automatically moves the member 15 out of engagement with the contact member 27, to the position shown in Fig. 1 thereby disconnecting the circuit.

The long bearing for the stem provides quick responsive and easy operation in establishing a circuit, when the button is pressed against at any point on its operative surface. The shape of the outer surface of the button provides a large area within which the operator can press to operate the contact member.

By employing a relatively long and relatively tight bearing, I insure the operation, without danger of binding, of the circuit controller no matter where the depressing power is applied to the upper portion of the push button member. It is also possible—and in some structures highly desirable—to so make the parts that there is scant clearance between the base member and the overhanging flange 20, thereby virtually closing

the structure to dirt, moisture, etc. Indeed, it is possible to make this clearance much less than shown in the embodiment of my invention here illustrated without interfering with the operation of the parts or inviting or endangering binding of the button member against the base member.

Various changes can be made in the details of construction described without departing from the spirit of my invention and the scope of the appended claims.

What is claimed is:—

1. In a push button electric circuit controller, the combination of a base member, electric circuit controlling contacts mounted on said base member and normally disassociated electrically from each other, a push button member adapted to be reciprocated with respect to said base member, extending over the top of said base member and provided with an annular peripheral flange overhanging the upper part of the sides of the base member and adapted to telescope with said base member when the push button member is reciprocated, a pair of relatively long bearings, one on the base member and one on the push button member, upon which said push button member reciprocates with respect to the base member, said bearings fitting tightly, preventing the tilting and insuring the reciprocation of the push button member with respect to the base member, means whereby the contacts are associated electrically when the push button member is reciprocated and means for returning said push button member to normal when released.

2. In a push button electric circuit controller, the combination of a cylindrical base member having a hollow portion therein, electric circuit contacts mounted in the hollow portion of the base member and normally disassociated from each other electrically, a mushroom shaped push button member mounted on said base member and adapted to be reciprocated with respect thereto, said push button member extending over the top of said base member and being provided with an annular peripheral flange overhanging the top part of the sides of the base member, a relatively long hollow bushing mounted in the base member with its bore in a vertical position, a downwardly extending pin rigidly connected to the push button member and extending through and tightly fitting in the bore of said bushing to permit and insure the reciprocation of said push button member with respect to the base member but to prevent the tilting of said push button member with respect to the base member when the push button member is reciprocated, said flange telescoping with the upper portion of said base member when the button is reciprocated, and means whereby the push button member causes the electrical

association of said contacts when said push button member is reciprocated and spring means for returning said push button member to normal when the same is released.

5 3. In a push button circuit controller, the combination of a base member, electric circuit controlling contacts mounted on said base member, a push button member adapted to be reciprocated with respect to said base member, provided with an annular peripheral flange overhanging the base member with scant clearance between the flange and the base member, said push button member telescoping the said base member when the 10 push button member is reciprocated, a pair of relatively long bearings, one on the base member and one on the push button member, upon which said push button member reciprocates with respect to the base member, said 15 bearings fitting tightly, preventing the tilting and insuring the reciprocation of the push button member with respect to the base member, means controlling said contacts governed by the push button member when 20 it is reciprocated and means for returning said push button member to normal when released.

4. In a push button electric circuit controller, the combination of a cylindrical base member having a hollow portion therein, electric circuit contacts mounted in the hollow portion of the base member and adapted to control an electric circuit, a mushroom shaped push button member mounted on said 25 base member and adapted to be reciprocated with respect thereto, said push button member extending over the top of said base member and being provided with an annular peripheral flange overhanging the top part of 30 the sides of the base member and having scant clearance therewith, a relatively long hollow bushing mounted in the base member with its bore in a vertical position, a down-

wardly extending pin rigidly connected to the push button member and extending 45 through and tightly fitting in the bore of said bushing to permit and insure the reciprocation of said push button member with respect to the base member, but to prevent the tilting of said push button member with 50 respect to said base member when the push button member is reciprocated, said flange telescoping with the upper portion of said base member when the button is reciprocated, and means whereby the push button member governs the said electrical contacts when said push button member is reciprocated and spring means for returning said push button member to normal when the 55 same is released.

5. In a push button electric circuit controller, the combination of a base member, electric circuit controlling contacts mounted on said base member, a push button member adapted to be reciprocated with respect to 60 said base member to control said contacts and extending over the top of said base member, a pair of bearings substantially as long as the radius of the push button member perpendicular to the long axis of the bearings, 65 one of said bearings being mounted upon said base member and the other bearing being mounted upon said push button member, said bearings fitting tightly one in the other, preventing the tilting and insuring 70 the reciprocation of the push button member with respect to the base member, an annular downwardly extending peripheral flange on the push button member adapted to telescope with the top of the base member when 75 the push button member is reciprocated.

In testimony whereof I hereunto affix my signature this 27 day of November, 1923.

MARY E. DEAN,
Executrix of William W. Dean, Deceased.
